UNITED STATES PATENT OFFICE

148,268

DESIGN FOR A BORDER MAT FOR A PICTURE FRAME OR SIMILAR ARTICLE

Joseph Amaru, Somerville, Mass.

Application August 20, 1947, Serial No. 140,956

Term of patent 14 years

(Cl. D29—20)

To all whom it may concern:

Be it known that I, Joseph Amaru, a citizen of the United States, residing at Somerville, in the county of Middlesex, in the Commonwealth of Massachusetts, have invented a new, original, and ornamental Design for a Border Mat for a Picture Frame or Similar Article, of which the following is a specification, reference being had to the accompanying drawing, forming a part thereof, in which:

I claim:

The ornamental design for a border mat for a picture frame or similar article, substantially as shown.

JOSEPH AMARU.
